F. M. LEE

FURNACE

Filed April 3, 1924

Fig. 1.

Patented Dec. 28, 1926.

UNITED STATES PATENT OFFICE.

FRANK M. LEE, OF CHICAGO, ILLINOIS, ASSIGNOR TO SULLIVAN MACHINERY COMPANY, A CORPORATION OF MASSACHUSETTS.

FURNACE.

Application filed April 3, 1924. Serial No. 794,052.

This invention relates to furnaces.

It has for its object to provide an improved furnace. A further object is to provide an improved furnace especially adapted to use with drill steels or other desired articles having improved combustion and heat distributing chambers. A further object is to provide an initial enlarged fuel combustion chamber which has communication with a relatively narrower chamber over which the drill steels to be heated are disposed.

In the accompanying drawings I have shown for purposes of illustration one form 15 which my invention may assume in practice.

In these drawings,—

Fig. 1 is a longitudinal transverse section of my improved furnace taken substantially on line 1—1 of Fig. 2, with parts broken 20 away.

Fig. 2 is a vertical transverse section taken on line 2—2 of Fig. 1.

In the illustrative form of my invention I have shown the same as comprising 25 a brick retaining rectangularly shaped box 1 mounted upon suitable supporting legs 2 and having at one end thereof outwardly projecting walls 3 which are spaced inwardly from the longitudinal sides of the 30 box 1 and connected by a transverse wall 4. Disposed in the bottom and sides of the box 1 are fire bricks 5 so spaced that a central vertical longitudinal opening 6 is formed between the adjacent ends of said 35 bricks. There is also disposed within the walls 3 and 4 an initial combustion and mixing chamber formed by central fire bricks 7 a considerable distance apart, and bricks 8 and 9 disposed on each end of said central 40 ones. The bricks 9 are tapered so that the initial combustion chamber will converge into the narrow chamber 6, which also prevents eddy currents or the like. The rear 45 bricks 8 have inclined surfaces terminating adjacent a burner 10 mounted within the transverse wall 4. Fuel and air may be supplied to the burner 10 by any suitable valve controlled supply pipes 11 and 12, while a finer degree of adjustment may be 50 had by a needle valve 13.

Disposed upon the top of the box 1 are transversely adjustably mounted bricks 14 upon which a drill steel 15 may rest so that the bit end thereof will lie over the opening 55 formed between the adjacent ends of the

bricks 14, while the shank end rests on a supporting bracket 16, this open space having communication with the narrow chamber 6. There are also bricks 17 longitudinally disposed over the bricks 14 and transversely spaced to form a relatively narrow passage 18 through which the combustible gases exhaust to the atmosphere, the size of this passage being regulated by any suitable control means 19 to suit temperature 60 conditions required by the different drill steels. It is to be noted that the initial combustion chamber formed by the bricks 7, 8 and 9 is closed at the top as by bricks 20. 65

It will be seen that in my improved furnace fuel upon first entering the initial combustion chamber will have a relatively large volume within which the constituent elements of the fuel may become intimately mixed for combustion so that a very highly 70 centralized heat will be directed against the ends of the steels. It has been found that by making one size of a continuous passage from the burner throughout the length of the furnace such an intense heat is not 75 obtained as in the present construction which is due to the double chambers of different sizes.

While I have in this application specifically described one form which my invention may assume in practice, it will be understood that this form of the same is shown for purposes of illustration and that the invention may be modified and embodied in various other forms without departing from 80 its spirit or the scope of the appended 85 claims.

What I claim as new and desire to secure by Letters Patent is:

1. A heating furnace comprising an elongated combustion chamber having a substantially horizontal plane bottom and comprising an enlarged portion for initially receiving the combustible mixture and an aligned elongated communicating restricted heating 100 portion, a narrow elongated passage communicating with the restricted portion of said chamber substantially throughout the length of the latter and through which the burned mixture from said chamber passes, and a 105 burner discharging longitudinally of said chamber, said plane bottom and restricted portion graduating the heat to a maximum temperature at the end of said chamber remote from the burner discharge. 110

2. A heating furnace comprising an elongated combustion chamber having a substantially horizontal plane bottom, a transversely enlarged portion for initially receiving the combustible mixture, and an aligned communicating transversely restricted heating portion, a narrow elongated passage communicating with the restricted portion of said chamber through which the burned mixture from said chamber passes, and a burner discharging longitudinally of said chamber, said horizontal plane bottom and said restricted portion graduating the heat to a maximum temperature at the end of said chamber remote from the burner discharge.
3. A heating furnace comprising an elongated combustion chamber having a substantially horizontal plane bottom, a transversely enlarged portion for initially receiving the combustible mixture, and an aligned communicating transversely restricted heating portion, said enlarged portion having a smooth surface converging with said restricted portion, a narrow elongated passage communicating with the restricted portion of said chamber through which the burned mixture from said chamber passes, and a burner discharging longitudinally of said chamber, said horizontal plane bottom and said restricted portion graduating the heat to a maximum temperature at the end of said chamber remote from the burner discharge.
4. A heating furnace comprising an elongated combustion chamber having a substantially horizontal plane bottom, a transversely enlarged portion for initially receiving the combustible mixture, and an aligned communicating transversely restricted heating portion, said portions having parallel side walls, a narrow elongated vertical passage communicating with the restricted portion of said chamber through which the burned mixture from said chamber passes, and a burner discharging longitudinally of said chamber, said horizontal plane bottom and said restricted portion graduating the heat to a maximum temperature at the end of said chamber remote from the burner discharge.
5. In a heating furnace comprising an elongated combustion chamber having a substantially horizontal plane bottom, an aligned transversely enlarged portion for initially receiving the combustible mixture, and a communicating transversely restricted heating portion, said portions having parallel side walls and smooth tapering surfaces connecting said side walls, a narrow elongated vertical passage communicating with the restricted portion of said chamber through which the burned mixture from said chamber passes, and a burner discharging longitudinally of said chamber, said horizontal plane bottom and said restricted portion graduating the heat to a maximum temperature at the end of said chamber remote from the burner discharge.
6. A heating furnace comprising an elongated combustion chamber having a substantially horizontal plane bottom, a transversely enlarged portion for initially receiving the combustible mixture, and a communicating transversely restricted heating portion, means for covering said restricted portion to form a variable opening through which the burned gases from said chamber pass, and a burner discharging longitudinally of said chamber, said horizontal plane bottom and said restricted portion graduating the heat to a maximum temperature at the end of said chamber remote from the burner discharge.
7. A heating furnace comprising an elongated combustion chamber having a substantially horizontal plane bottom, a transversely enlarged portion for initially receiving a combustible mixture, and a communicating transversely restricted heating portion, said portions having parallel side walls and smooth surfaces connecting said side walls, means for covering said restricted portion to form a variable opening through which the burned gases from said chamber pass, and a burner discharging longitudinally of said chamber, said horizontal plane bottom and said restricted portion graduating the heat to a maximum temperature at the end of said chamber remote from the burner discharge.

In testimony whereof I affix my signature.

FRANK M. LEE.
